UNITED STATES PATENT OFFICE.

JOHN A. HOLMBERG, OF LINDSBORG, KANSAS.

STEAM-TRAP FOR VAPOR-HEATING SYSTEMS.

1,373,072.

Specification of Letters Patent.

Patented Mar. 29, 1921.

Application filed August 21, 1919. Serial No. 318,931.

To all whom it may concern:

Be it known that I, JOHN A. HOLMBERG, a citizen of the United States, residing at Lindsborg, in the county of McPherson and 5 State of Kansas, have invented certain new and useful Improvements in Steam-Traps for Vapor-Heating Systems; and I do declare the following to be a full, clear, and exact description of the invention such as 10 will enable others skilled in the art to which it appertains to make and use the same.

This invention relates to steam heating systems and more particularly to that class known as vacuum systems wherein a low or 15 less than atmospheric pressure is utilized and in which it is necessary to first empty the radiators and connections of air and water and thereafter prevent the reentry of air thereinto and maintain at least a partial vacuum in the system.

Various means have been devised for venting the air from the radiators, including automatic or thermostatic valves located at the radiators, vacuum pumps and others subject to the defects of a low circulation, 25 pounding, back pressure, discharge of foul air and water into the rooms, increased cost of installation and attendance, and the like.

It is therefore the primary object of the 30 present invention to provide an apparatus free from such defects and characterized by the improved means for venting the air from the radiators by a trapping and ejecting device located at one point and discharging 35 such air outside the building or rooms and for sealing the system against the return of air.

Another object of the invention is to so construct a trapping and air ejecting device of 40 this character in which water entering with the air or steam is quickly and thoroughly separated therefrom, permitting the air to rise and pass out in one direction and the water to flow down and pass out in another 45 direction.

A further object of the invention is to construct a trap of this character so that the water and steam entering it will be deflected and brought into whirling contact with the 50 walls thereof and thereby thoroughly cleanse said walls and prevent the accumulation of grease and other foreign matter thereon.

A very important improvement over 55 steam traps now known and used and present in this invention resides in the construction of the check valve which prevents the

air from entering the system from the outside. The seat of this check valve is so constructed that no particles of dust, dirt, grease or other foreign matter will accumulate thereupon and prevent the proper seating of the valve. Any of this foreign matter present in the neighborhood of the valve will be blown away as air is passing through the same.

An additional object of the invention is to provide a steam trap of this character which will be extremely simple, strong, durable and inexpensive in construction, one which will be efficient and reliable in operation and well adapted to the purpose for which it is designed.

With these and other objects in view, the invention consists of certain novel features of construction and the combination 75 and arrangement of parts as will be herein-after fully described and claimed.

In the accompanying drawings in which similar reference characters designate like parts throughout the several views;

Figure 1 is a central vertical sectional view of a steam trap constructed in accordance with this invention.

Fig. 2 is a transverse sectional view taken on the plane indicated by the line 2—2 of Fig. 1, and

Fig. 3 is a diagrammatic view of a steam heating system equipped with one of the improved traps.

In the embodiment illustrated, a boiler or 90 steam generator A of any suitable construction is shown having a steam pipe B provided with suitable branches C leading to radiators D. Valves are provided at E for controlling the inlet of the various radiators.

A return pipe indicated at F is connected with suitable branches G leading from the radiators D and with the water space of the generator, said pipe being here shown provided with a vertically disposed portion H which connects the main portion thereof with the boiler. In order to prevent water from backing up in the return pipe H when the boiler is forced, a swing check valve H' 100 is placed in the pipe H. In the preferred embodiment of the invention a combined steam trap and air vent 1 is located near the end of the return line F at a point above the plane where said line drops below the 110 water level in the boiler and is disposed adjacent the junction of the horizontal main

line F and the vertical portion H. This improved trap 1 comprises a casing which may be of any suitable form being here shown in the form of a cylinder having a removable closure or cover plate 2 at its upper end and with an inlet 3 extending tangentially through one side wall thereof near its upper end. This inlet 3 is connected by a pipe I with the main or return line F, the connection of said pipe with the trap being in a plane above its connection with said return line. By so connecting the pipe I with the trap and the return line the air and water forced through the return line F by the pressure exerted by the incoming steam is caused to separate at this point, the air rising through the pipe 3 and entering the trap 1 while the water flows by gravity down through the vertically disposed portion H of the return pipe back to the water space of the boiler. The object in disposing the inlet 3 tangentially of the casing is to cause the entering fluid to impinge against the side wall of the trap and thereby thoroughly separate the air and water contained therein.

The upper side of the cover 2 is provided with a centrally disposed boss or enlargement 4, the latter having a longitudinal opening 5 extending therethrough and a transverse opening 6 communicating with the latter. The upper and lower ends of the opening 5 are internally threaded. Fitted in the threaded lower end of the opening 5 is a bushing 7, the lower end of which is provided with a head having a flat lower side. Extending longitudinally through the bushing 7 is an opening 8, the junction of the lower end of which with the flat lower side of the head of the bushing is rather sharp and forms a valve seat. The upper end of the bushing 7 is beveled as at 9 and extends into an enlarged portion 10 of the opening 5 at the junction of the same with the opening 6. By this construction an annular space is left around the upper end of the bushing 7. Seated upon the upper end of the bushing 7 is a ball valve 11, the latter being capable of vertical movement, but being retained within a certain space so that it will automatically seat itself by gravity when air has ceased to flow upwardly through the opening 8 by a retaining plug 12. By beveling the upper end of the bushing 7 and by forming an annular space around the same, there will be no surface upon which dust, dirt, grease or foreign matter will accumulate and thus prevent the tight and proper seating of the valve 11.

The lower end of the trap 1 is provided with a discharge opening 13 and an internally threaded nipple 14 to which one end of a pipe J is threaded to connect the trap with the vertical portion H of the return pipe, the point of connection of the pipe J with the pipe H being below the water level

in the boiler. This pipe J is designed as a means for conveying the water which accumulates in the trap back to the generator. Threaded in the discharge opening 13 and rising vertically and centrally within the trap 1 is a pipe 15, the wall of the latter near its lower end being provided with an opening 16 effecting communication with the interior of the trap and the discharge opening 13, and the other end being disposed a short distance below the lower side of the closure 2.

The numerals 17 designate an inverted cup-shaped or dome-shaped float which has disposed within its upper end a partition 18, between which and the latter is arranged a thermostatic space 19. The partition 18 carries a lug 20 which is disposed within the upper end of the pipe 15 and serves as a guide for the float 17. The float 17 rests upon the pipe 15 with its lower end spaced above the bottom of the trap 1. The upper end of the pipe 15 carries a valve 21 adapted to be seated upon the seat formed at the junction of the opening 8 in the bushing 7 and the flat lower side of the head thereof.

In the operation of a low pressure or vapor heating system equipped with this invention when steam is generated in the boiler A it is immediately distributed through the system by passing through the pipes B and C into the radiators D and forces out therefrom air and the water of condensation which is contained in said radiators as a result of the lowering of the pressure in the system and the cooling off of the radiators. The entrance of steam into the radiators forces this air and water through the branch pipes G into the main portion of the return line F and it is driven through said main line back toward the water space of the boiler. On nearing the end of the line F the air and water encounters the inlet pipe I of the trap 1 arranged in the system adjacent the junction of the horizontal main line F and its vertical terminal H. When the air and water reach this point the water flows by gravity down to the pipe H while the moist air and possibly a small amount of water carried thereby rise through the pipe I and enter the trap casing 1 at a tangent through the opening 3. This air forced into the casing through the tangentially disposed opening 3 impinges violently upon the opposed wall of the casing and is whirled around therein whereby the moisture contained in the air is separated therefrom and trickles down the side walls of said casing and drains through the opening 16 into the water outlet 13 and thence through the pipe J to the vertically disposed pipe H and back to the water space of the boiler. The air freed from the water by this contact with the casing wall rises in the casing and passes out of the air dis-

charge to the atmosphere, the valve 21 being normally opened. If the separation of the water from the air or the condensation of the steam carried into the casing with the air takes place rapidly so that a considerable quantity of water accumulates within the casing and will not rapidly drain off, the float 17 will rise and close valve 21 so that if more water accumulates in the casing none of it will pass out of the air discharge. It is to be understood that the maximum amount of water allowed to accumulate in the casing is controlled by the weight of the float 17. As soon as this quantity of accumulated water passes out of the casing, the valve 21 will be opened by the lowering of the float 17 which carries it. After the air in main line F and in fact in the entire system has been discharged through the air discharge, steam enters the trap casing 1 through the opening 2 at a point in close proximity to the thermostat 19 and the heat thereof will immediately cause the thermostat to expand and thereby firmly close the valve 21. This prevents the escape of steam from the trap and causes it to pass back into the system. The check valve 11 prevents air from the outside atmosphere from gaining entrance to the interior of the casing. This valve being a ball valve and seated upon a sharp seat having no broad flat portion and being surrounded by an annular channel or space will not collect dust or other foreign matter and prevent the valve from properly seating. Therefore, the check valve will not leak and by this addition it greatly improves the system.

Attention is directed to the fact that the float 17 may rotate and the inlet 3 will direct the incoming fluid tangentially against said float. This causes rotation of the float and when the valve 21 is closed, produces a

grinding action on said valve and its seat to at all times insure a fluid-tight seating.

Various changes in form, proportion, and in the minor details of construction may be resorted to without departing from the spirit of the invention as defined in the claims.

What is claimed is:

1. A combined air ejector and trap comprising a casing having a fluid inlet, the top of said casing having an air outlet provided with a check valve and the bottom of said casing being provided with a water outlet, a pipe rising from said water outlet and having an open upper end below and alined with said air outlet, the lower end of said pipe having an opening placing the casing in communication with the water outlet, a float bell in said casing with its top over said pipe and provided with a valve for said air outlet, a partition in said bell below said top and forming therewith a thermostat for bowing said top upwardly and closing its valve, and a lug depending from said partition and slidably received in the open upper end of said pipe. 5

2. A combined air ejector and trap comprising a vertically disposed cylindrical casing having a water outlet and provided with an air outlet in its upper end, a valve for closing said air outlet, a cylindrical float rotatable in the casing and carrying said valve, the float wall and casing wall being in close proximity with each other, and a tangential fluid inlet through said casing wall below the upper end of said float wall, whereby to direct the incoming fluid against the float to rotate the latter for the purpose set forth. 75

In testimony whereof I have hereunto set my hand.

JOHN A. HOLMBERG.
